UNITED STATES PATENT OFFICE.

HERMAN A. POPPENHUSEN, OF EVANSTON, ILLINOIS.

TRAVELING-GRAVE FURNACE.

No. 896,410.

Specification of Letters Patent.

Patented Aug. 18, 1908.

Application filed January 8, 1907. Serial No. 351,307.

To all whom it may concern:

Be it known that I, HERMAN A. POPPENHUSEN, a citizen of the United States, and a resident of Evanston, in the county of Cook and State of Illinois, have invented certain new and useful Improvements in Traveling-Grate Furnaces; and I do hereby declare that the following is a full, clear, and exact description thereof, reference being had to the accompanying drawings, and to the letters of reference marked thereon, which form a part of this specification.

This invention relates to improvements in furnaces of that class embracing a traveling or chain grate on which the fuel rests and by which it is carried along or through the furnace during the process of combustion, and more especially to an improved means for keeping separate from the ashes discharged from the rear ends of the grate particles of unconsumed fuel which fall through the said grate and for removing such ashes from the ash-pit.

The invention consists in the matters hereinafter described and pointed out in the appended claims.

My invention may be more readily understood by reference to the accompanying drawings, in which my invention is shown in connection with a boiler-furnace.

In said drawings:—Figure 1 is a view in central longitudinal section of a boiler-furnace together with a conveying or ash-removing device embodying my invention. Fig. 2 is a view in transverse vertical section of the ash-pit and conveying device, said section being taken on the line 2—2 of Fig. 1. Fig. 3 is a perspective view of part of my conveying device.

As shown in said drawings, A (Fig. 1) indicates an endless traveling chain grate forming part of an automatic stoking device. Said endless traveling grate A is supported by sprocket wheels b b mounted in a frame B which is provided with supporting wheels b' b'. Said wheels b' b' rest and travel upon horizontal track rails C C which are located at the level of the furnace room floor and extend into the furnace chamber from front to rear and outwardly through the front opening of the furnace, so as to permit the grate supporting frame and grate to be withdrawn from the furnace when desired. The

grate and its support are arranged in the same manner as heretofore common in 55 boiler-furnaces.

D D indicate the side walls and D' the bottom wall or floor of the ash-pit. Said bottom wall or floor is located considerably below the level of the rails C C and of the furnace room floor and is, in its main part, flat and horizontal or approximately so. At its forward end, said ash-pit floor terminates at a pit or depression D² located adjacent to the forward end of the grate and preferably provided with a vertical rear wall d and an upwardly and forwardly inclined front wall d'. Beneath the track rails C C, and supporting the same, is a horizontal partition E separating the forward part of the furnace chamber 70 from the part of the ash-pit below it. As illustrated in the drawings, said partition E consists of metal plates supported by transverse bars e e e. Said partition E terminates forward of the rear end of the grate, leaving 75 at the rear of the furnace an open space through which ashes and burned-out fuel discharged at the rear end of the grate may fall to the bottom of the ash-pit. At the rear end of the partition is located a bridge- 80 wall E' which rises from the partition and terminates near the level of the bottom of the supporting frame B of the grate.

F F indicate two rods which extend longitudinally of the furnace and are arranged parallel with each other and parallel with and at a short distance above the ash-pit floor. Said rods are supported or suspended by suspension members f f from the partition E above them. Said suspension members f f are 90 flexibly connected with the rods and with the partition so as to permit longitudinal movement of the rods F F.

As shown in the drawings, the suspension members f f consist of chains which are connected at their upper ends with the transverse supporting bars e e e of said partition E. Connected with the rods F F, below the same, are a plurality of transverse, vertically arranged plates G G which are flexibly connected at their upper edges with the said rods and are arranged at uniform distances apart along said rods, which latter extend rearwardly of the rear margin of the partition E to points above the rear end of the 100 ash-pit floor; the rearmost of the said plates

G being located near the rear end of said floor. Said plates G G are so connected with the rods F F that the plates will be held from swinging backwardly from the upright or 5 vertical position thereof, but their lower edges are free to swing upwardly or forwardly.

As shown in the drawings, the said plates are connected at their upper margins with 10 the said rods by means of links g which pass through holes in the plates and are engaged with loops or rings f^1 attached to the rods; this construction affording a flexible or 15 hinged connection between the upper edges of the plates and said rods. In the construction illustrated, moreover, the said plates are held from swinging rearwardly from the vertical position thereof by means of diagonally arranged flexible, connecting members or 20 chains g^1 g^1 , which are attached at their lower ends to the plates near the bottom edges thereof, extend upwardly and forwardly from their points of attachment to the plates and are secured at their upper 25 ends to the said rods at points forward of the plates.

Endwise reciprocatory motion is given to the rods F F by means as follows: H is a horizontal rotative shaft arranged transversely with respect to the rods F F and located at the front of the ash-pit about at the level of the said rods. Said shaft H is provided with two eccentrics, one of which is indicated at h . The eccentrics are connected 30 with the forward ends of the rods F F by means of rods, one of which is shown in Fig. 1 at H^1 .

The rods F F, being suspended by suspension members ff , as described, the effect of 40 giving endwise movement to said rods by the eccentrics, as described, is to impart to the rods an oscillatory or swinging motion in curved paths, the rods rising and falling as they are moved backward and forward from the central or depressed position thereof. The plates G G are correspondingly moved or 45 swung; rising and falling relatively to the floor of the ash-pit as they are moved backwardly and forwardly over the same. The said plates are supported at such elevation 50 that when the rods F F are depressed and the plates hang freely from the rods, they will stand approximately in a vertical position with their lower edges in contact 55 with the ash-pit floor, or closely adjacent thereto. Preferably they come in actual contact with or rest upon the floor when the rods are in their depressed or central position. As a result of the hinged connection of the 60 said plates G G with the rods F F, and the employment of means limiting the backward swing of the said plates from the vertical position thereof, said plates, in the backward movement of the said rods, will swing forwardly or rise and pass over any ashes rest-

ing on the floor of the ash-pit, but will resume their upright positions and scrape or carry forward along the floor the ashes engaged by the lower edges thereof in the lower movement of said rods. The backward and forward movement of the rods and plates will therefore have the effect of dragging or scraping forward all of the ashes on the ash-pit floor, and this result will follow whether the supporting rods F F be hung or supported so 70 as to rise and fall in their endwise movement or not. It is preferred, however, to suspend the rods in the manner illustrated, the effect of the rising and falling movement thereby imparted to the rods being that the scraping plates carried thereby move in curved paths and come into contact with the ash-pit floor when advancing and in their depressed positions; the lower edges of said plates being lifted above the ashes when they reach the 75 rearward end of their stroke and also at the termination of their forward stroke. The result of the movement of the plates in curved paths, therefore, is that the mass of ashes on the ash-pit floor will be advanced in 80 the form of separate transverse piles or ridges, over the tops of which the lower edges of the plates will be dragged in their backward movements, and which will be carried bodily forward at each forward movement of said 85 plates. The employment of swinging suspension members for the rods, as illustrated, has the advantage of providing a very simple means for movably supporting the rods, which is cheap in construction and not liable 90 to get out of repair, while at the same time affording an effective action in the plates in advancing the ashes along the ash-pit floor.

The ashes advanced along the ash-pit floor are delivered from the forward end of the latter into the pit or depression D².

I have shown in the accompanying drawings a depressed runway or channel I as extending along the front of the furnace adjacent to the pit D², and adapted for the passage therethrough of an ash-receiving car J, the top of which is located about at the level of the top of the inclined front wall d¹ of the said pit D². At the top of said wall d¹ is located a plate d² which forms a continuation 110 of the top surface of said wall, and overhangs the car J. By this construction, ashes deposited in the pit D² may be easily scraped therefrom upwardly along the wall d¹ and into the car J, by which they may be removed to a desired place of deposit.

The rods F F constitute in effect a supporting frame or member for sustaining and giving bodily movement to the scraper plates, inasmuch as said rods have equal simultaneous movement, and although shown in the drawings as separate from each other, operate in the same manner as though they were rigidly connected with each other or constituted part of a single frame.

One important feature of my invention is embraced in a construction in which there is present, in connection with an endless traveling grate, a horizontal partition located beneath the forward part of the said grate and forming a horizontal passage between the latter and bottom wall or floor of the ash-pit and which is adapted to receive and keep separate from the ashes the particles of unburned fuel which fall through said chain grate, and conveying means located in said longitudinal passage between said horizontal partition and the bottom or floor of the ash-pit, embracing a plurality of scraper plates having swinging movement in one direction from the upright position thereof and bodily reciprocating movement, said plates being in length substantially equal to the width of the ash-pit floor and acting to advance the ashes which descend to said ash-pit floor from the rear end of the grate at the rear end of said horizontal partition, forwardly beneath said partition to the front end of the furnace.

Other important features of the invention are embraced in certain details of construction and arrangement of the said conveying mechanism as pointed out in the appended claims.

I claim as my invention:—

1. In a furnace, the combination with an ash-pit having a substantially horizontal floor and a horizontally arranged traveling grate, of a partition located beneath the grate forward of the rear end of the said grate and between the same and the ash-pit floor, and means for conveying ashes which descend from the rear end of the grate to the ash-pit floor forwardly beneath said partition, comprising a substantially horizontal, endwise reciprocating, supporting member, extending longitudinally of said passage, and a plurality of scraper plates located transversely in said longitudinal passage and acting on the ash-pit floor, said scraper plates having flexible connection with and depending from said supporting members, and having a swinging movement in one direction only from the upright position thereof, and actuating means for reciprocating said supporting member, located forward and outside of the furnace.

2. In a furnace, the combination of an ash-pit, having a substantially horizontal floor, and a horizontally arranged traveling grate, of a horizontal partition located beneath the grate forward of the rear end of said grate, said partition forming with the ash-pit floor, a longitudinal passage for the removal of ashes from the rear end of said grate to the forward end of the furnace, and means located in said passage for conveying ashes which descend from the rear end of the grate to the ash-pit floor, forwardly beneath said partition, comprising a substantially horizontal, endwise reciprocating, supporting mem-

ber extending longitudinally of said passage, a plurality of suspension members having flexible connection with the said partition and said supporting member, affording a swinging movement in the supporting member, a plurality of scraper plates located transversely in said longitudinal passage, and acting on the ash-pit floor, said scraper plates having flexible connection with and depending from said supporting member, said scraper plates having swinging movement in one direction only from the upright position thereof, and actuating means for reciprocating said supporting member, located forward and outside of said furnace.

3. The combination with a supporting surface on which rests the material to be moved, an endwise reciprocating supporting member located above said surface, swinging suspension members sustaining said supporting member from above, a plurality of swinging scraper plates carried by and located transversely below said supporting member, and flexible connecting members extending obliquely from the lower parts of said plates upwardly to the said supporting member.

4. The combination with a supporting surface on which rests the material to be moved, parallel supporting rods located above the floor, swinging suspension members supporting said rods, scraper-plates located transversely beneath the said rods and flexibly connected with the same, said plates having swinging movement relatively to the rods in one direction only from the upright position thereof, and means for giving endwise movement to the said supporting rods, comprising a rotative shaft provided with eccentrics and eccentric rods connecting the said eccentrics with the said supporting rods.

5. The combination with a furnace grate and an ash-pit floor beneath the same, of a horizontal partition located between said grate and the said ash-pit floor, parallel supporting rods located in the space between said partition and the ash-pit floor, suspension members connected at their upper ends with the partition and at their lower ends with said rods, scraper plates located transversely of the rods below the same and flexibly connected with said rods, said plates having movement in one direction only from the upright positions thereof and means connected with said rods for giving endwise reciprocating motion to the same.

6. The combination with an ash-pit floor, of means for moving ashes forwardly along said floor, an ash receiving pit located at the forward end of said floor, said pit being provided with an inclined front wall, a depression or channel extending transversely of the furnace in front of the said receiving pit, and an ash receiving car adapted to move or travel through said channel.

7. The combination with an ash-pit floor,

of means for moving ashes forwardly along said floor, an ash receiving pit located at the forward end of said floor, said pit being provided with an inclined front wall, a depression or channel extending transversely of the furnace in front of the said receiving pit, and an ash receiving car adapted to move or travel through said channel, said front wall of the said ash receiving pit being provided 10 at its upper margin with a plate which over-

hangs the said channel and the adjacent side of the car therein.

In testimony, that I claim the foregoing as my invention I affix my signature in the presence of two witnesses, this 3d day of January 15 A. D. 1907.

HERMAN A. POPPENHUSEN.
